HUMIDIFIER

Francis A. Furlong and Norman C. Penfold, Chicago, Ill., assignors to Autogas Company, Chicago, Ill., a corporation of Illinois

Application September 11, 1940, Serial No. 356,270

7 Claims. (Cl. 122—332)

This invention relates to humidifiers and more particularly to the type for evaporating water and supplying vapor to living spaces and the like.

It has been found in the operation of humidifiers particularly in those sections in which the water is hard the operating parts tend to become coated with a deposit of scale so that after a relatively short time the efficiency of the humidifier decreases rapidly. This is due not only to the insulating effect of such scale deposits but also to the clogging of passages for the flow of steam or water.

It is one of the objects of the present invention to provide a humidifier in which deposition of scale is eliminated. According to one important feature of the invention this is accomplished by periodically draining the water from the humidifier and flushing the humidifier parts so that a sufficient concentration of mineral matter in the water to cause deposition is avoided.

Another object of the invention is to provide a humidifier which is periodically automatically drained and flushed.

Still another object of the invention is to provide a humidifier in which the admission of water is dependent upon steaming and in which the maintenance of a predetermined water supply is assured for operation of the water admission means.

The above and other objects, advantages and novel features of the invention will be apparent from the following description when read in connection with the accompanying drawings, in which:

Figure 1 is a sectional view of a humidifier proper; and

Figures 2 and 3 are diagrammatic views illustrating alternative installations.

The humidifier shown in Figure 1 includes a tank having an enlarged upper portion 10, and a reduced lower portion 12 at one side of the upper portion. A horizontal connecting wall 14 forms a partial bottom for the upper portion and serves to join the upper and lower portions.

The tank is adapted to contain water substantially to the midpoint of the upper portion as shown and water in the upper portion is heated by a burner 16 mounted below the horizontal wall 14. Preferably an insulating block 18 is arranged between the burner and the tank portion 12 to prevent heating of the water therein. The burner discharges into a passage formed by a jacket 20 extending across the wall portion 12 and up one side of the tank 10 to a flue 22.

Water is admitted to the tank through a pipe 24 terminating in a nozzle closed by a valve carried by the free end of a bi-metal strip 26. The strip 26 is mounted at its upper end in the top part of an open pipe 28 lying beside the tank and communicating with the bottom of the lower tank portion 12. A horn member 30 is connected to the pipe 28 adjacent the strip 26 and terminates in a downwardly facing opening lying at the desired water level. When the water level drops, steam from the tank flows through the horn member 30 and out the open end of the pipe 28, heating the strip 26 and causing the valve to open to admit more water. If desired, the valve may be opened manually by a pin 32 connected to the strip 26 and extending through the side of the pipe 28.

In normal operation vapor formed in the tank is discharged through an outlet nozzle 34 and 20 may be conducted therefrom to any desired point of use. The nozzle is preferably provided with a restricted orifice plate 36 offering greater resistance to the flow of steam than the horn member 30 so that when the water level drops 25 substantially all of the generated steam will flow through the horn member. The construction as so far described is substantially identical with that more particularly described and claimed in our co-pending application, Serial No. 319,228 filed September 16, 1940.

According to the present invention water is removed from the tank by a pump means shown in Figure 1 as comprising a water operated ejector 38. A nozzle 40 in the ejector communicates 35 with a water pipe 42 which is connected through a spray nozzle 44 with the water inlet pipe indicated at 46. Valve 48 controls the flow of water through the pipes 46 and 42.

As best seen in Figure 2, the valve 48 is electrically operated and is controlled by a mercury switch 50. The mercury switch 50 is pivotally mounted and tends normally to tilt to its closed position but is controlled by a cam disk 52 driven by a suitable clock motor or the like not shown. 45 When the switch 50 is closed the valve 48 is connected to a power source shown as a transformer 54 and is opened to admit water from the main 56 into the pipe 46. From this pipe water flows to the nozzle 44, a portion of it spraying into the upper part of the tank and the remainder flowing through the pipe 42 to the injector nozzle 40.

The cam disk 52 is so shaped as normally to hold the switch 50 in open position but is provided with a low spot for periodically closing the switch 50 to energize the valve 48. The low spot

is preferably so arranged as to maintain the valve open for a relatively short period of time as for example, two minutes, and may be driven at such a speed as to open the valve at any desired interval depending upon the hardness of the water. When the valve is opened the ejector is operated to pump water from the tank and at the same time water sprays from the nozzle 44 into the tank to wash any deposits from the walls thereof. Water spraying from the nozzle 44 also cools the tank so that steaming will not occur during the draining period and so that the water pipe 24 will remain closed during this period. When the cam operates to again open the switch 50 the valve 48 will be closed and the humidifier will continue to operate in its normal manner.

Due to the construction of the tank with the reduced lower portion 12 containing relatively cool water any minerals precipitated from the water will tend to collect in this portion and will be pumped therefrom by the ejector. This insures that the tank is kept clean and in good operating condition at all times.

In order to insure operation of the water admitting means after the tank has been drained provisions are made to retain a minimum amount of water in the tank at all times. As shown, this is effected by providing a short wall 58 extending upwardly from one side of the wall portion 14 at which it connects with the tank portion 12. The wall 58 retains a pool of water above the wall 14 so that after the tank is drained steam will be formed to heat the bimetal strip 26 thereby to open the end of the water pipe 24 so that water will be admitted to the tank.

The construction of Figure 3 is substantially similar to that of Figures 1 and 2 and parts therein corresponding to like parts in Figures 1 and 2 have been designated by the same reference numerals. In this construction the pipe 46 communicates with the nozzle 44 and terminates at that point so that all of the water flowing therethrough will be sprayed into the tank. The ejector 38 of Figures 1 and 2 has been replaced by a gear pump 60 driven by a motor 62 and connected to the lower part of the pipe 28. The motor 60 and the valve 48 are both controlled by the mercury switch 50 so that when the valve is open the motor will be energized. The operation of this construction is substantially identical to that described above in connection with Figures 1 and 2 and will not be repeated.

While two embodiments of the invention have been illustrated and described in detail it will be understood that these are not intended as a definition of the scope of the invention, reference being had for that purpose to the appended claims.

What is claimed is:

1. A humidifier comprising a tank to contain water, means for heating water in the tank to vaporize it, a horn member in the tank terminating in a downwardly facing opening at the desired level of water in the tank, means operated by flow of steam through said horn member when the water level falls below said opening for admitting water to the tank, means for periodically draining the water from the tank, and spray means operable simultaneously with the draining means and so positioned in the tank as to flush it, the water being of such temperature that the formation of steam during the flushing and draining operation does not take place.

2. A humidifier comprising a tank to contain water, means for heating water in the tank to vaporize it, a horn member in the tank terminating in a downwardly facing opening at the desired level of water in the tank, means operated by flow of steam through said horn member when the water level falls below said opening for admitting water to the tank, means for periodically draining the water from the tank, spray means operable simultaneously with the draining means and so positioned in the tank as to flush it, the water being of such temperature that the formation of steam during the flushing and draining operation does not take place, and means in the tank to retain a relatively small volume of water therein whereby steam will be formed to operate the water admitting means during draining.

3. A humidifier comprising a tank having an enlarged upper portion and a reduced lower portion joined by a substantially horizontal wall, means for heating said wall to vaporize water in the tank, means to drain water from the tank communicating with said reduced lower portion, and means to retain a minimum level of water above said wall.

4. A humidifier comprising a tank having an enlarged upper portion and a reduced lower portion joined by a substantially horizontal wall, means for heating said wall to vaporize water in the tank, means to drain water from the tank communicating with said reduced lower portion, a horn member in the tank terminating in a downwardly facing opening at a level above said wall, means operated by the flow of steam through said horn member when the level of the water drops below the opening to admit water to the tank, and means to retain a minimum level of water above said wall during draining to initiate operation of the water admitting means after draining.

5. A humidifier comprising a tank having an enlarged upper portion and a reduced lower portion joined by a substantially horizontal wall, means for heating said wall to vaporize water in the tank, means to drain water from the tank communicating with said reduced lower portion, a horn member in the tank terminating in a downwardly facing opening at a level above said wall, means operated by the flow of steam through said horn member when the level of the water drops below the opening to admit water to the tank, means to retain a minimum level of water above said wall during draining to initiate operation of the water admitting means after draining, said drain means including water operated pump means, a spray nozzle in the upper part of the tank, and control means for periodically simultaneously admitting water to said pump means and spray nozzle the temperature of the water discharged from the spray nozzle being such that formation of steam does not take place during the draining and spraying operation.

6. A humidifier comprising a tank to contain water, means for heating water in the tank to vaporize it, means operated by heated vapor from the tank to maintain a predetermined level of water in the tank, means for periodically draining water from the tank, and spray means operable simultaneously with the draining means and so positioned in the tank as to flush it, the water being of such temperature that the formation of heated vapor to operate the water level

maintaining means during the flushing and draining operation does not take place.

7. A humidifier comprising a tank to contain water, means for heating water in the tank to vaporize it, means operated by heated vapor from the tank to maintain a predetermined level of water in the tank, means for periodically draining water from the tank, and spray means operable simultaneously with the draining means and so positioned in the tank as to flush it, the 10

water being of such temperature that the formation of heated vapor to operate the water level maintaining means during the flushing and draining operation does not take place, and 5 means in the tank to hold a minimum quantity of water therein to initiate operation of the water level maintaining means when the draining means is inoperative.
